UNITED STATES PATENT OFFICE

LESTER PIERCE BOLL, OF MAPLEWOOD, AND THEODORE BIRKENMAIER, OF ST. LOUIS, MISSOURI, ASSIGNORS TO W. N. MATTHEWS CORPORATION, OF ST. LOUIS, MISSOURI, A CORPORATION OF MISSOURI

SWITCH

Application filed August 16, 1928. Serial No. 300,058.

This invention relates to switches and with regard to certain more specific features, to fuse switches and the like, of the box or case type for expulsion fuses.

5 Among the several objects of the invention may be noted the provision of a simplified box type of fuse switch incorporating a compact combined double tube and movable bottom construction and having readily removable 10 contacts in the mounting of which molded supporting means are entirely eliminated, whereby means is afforded for producing a switch assembly of minimum dimensions and manufacturing cost with maximum usefulness. Other objects will be in part obvious 15 and in part pointed out hereinafter.

The invention accordingly comprises the elements and combinations of elements, features of construction, and arrangements of 20 parts which will be exemplified in the structure hereinafter described, and the scope of the application of which will be indicated in the following claims.

In the accompanying drawings, in which is 25 illustrated one of various possible embodiments of the invention,

Fig. 1 is a side elevation of the switch shown applied to a cross arm;

Fig. 2 is a vertical section taken through 30 the switch, certain parts being shown in alternate dotted-line positions;

Fig. 3 is a front elevation of the switch, certain portions being broken away;

Fig. 4 is a bottom plan view of the switch; 35 and,

Fig. 5 is a fragmentary front elevation of the lower portion of the switch.

Similar reference characters indicate corresponding parts throughout the several 40 views of the drawings.

Referring now more particularly to Fig. 1, there is illustrated at numeral 1 a case or housing composed preferably of porcelain, bakelite or other insulating material. This 45 case or housing 1 is supported from an adjustable mast arm 3 adapted to be fastened to a cross arm 5 (see Fig. 1). The support between the mast arm 3 and the case or box 1 is effected by means of a bolt 7 held to the 50 box by means of alloy, cement or other simi-

lar material. The fastening is at the top of the box only, thereby permitting free expansion and putting the box material in compression when a fuse blows, as will appear hereinafter. In effect the mounting is a sus- 55

A door 11 made of insulating material is hinged to said box 1 on a tube 13, thereby forming an upwardly opening closure for the front of the box (see Fig. 2). A finger piece 60 15 is provided at the bottom of said door or closure 11. The door, when shut, rests in parallel recesses 17 formed in the side walls 21 of the case 1. Interposed between the upper portion of door 11 and the side walls 21 are 65 two spring washers 23 on the pin 13. Said spring washers 23 are adapted to hold the door 11 in open position, when opened past its dotted-line position indicated in Fig. 2.

In its closed position, door 11 is so held 70 by a strap 24 of spring material, the end portions 26 thereof being bent at slightly less than right angles, for gripping the sides 21 of the case 1. (See Figs. 1 and 4.) The strap 24 is held to the door by means of two screws 75 28, which are screwed into a pair of plugs 30 of alloy, or the like.

A novel feature of the invention is in the 80 mounting of a pair of spring terminal engaging elements or clips 25. These clips each 85 comprise a pair of U-shaped spring members 27 riveted to terminal members 29, the latter being composed of metal and bored at 31 to rotatably receive metallic tubular pins 32, the latter being provided at both ends with 85 eccentric sleeves 33, lightly fitted thereon. The sleeves 33 are positioned in sideward openings 34, formed in the walls 21 of the case 1. This arrangement permits adjusting the alignment of the cartridge tube 53 and 90 the clips 25 during assembly. It is to be understood that the openings 34 are preferably formed during the molding process used in making the box.

It will be seen from Fig. 2 that each terminal member 29 comprises a rocker having an upper arm 35 and a lower arm 37, the latter being provided with a set screw 39 passing therethrough and engaging the back of the box 1. By backing off the set screws 39, spaces 100

are provided whereby the hollow terminal hinge pins 32 (including their eccentrics) may be passed loosely through the openings 34 and also through said rocker members 29. 5 In order to tighten the members 29 in place it is only necessary to screw down the set screws 39, whereupon they engage the back of the box and fulcrum the members 29 on their upper arms 35, thereby swinging the 10 lower portions of the members 29 in such fashion as to force the eccentrics of the hollow pins 32 against the sides of their openings 34. Hence, without any molding requirements, there is provided a set of supports for the terminal clips 25 and at the 15 same time a support for certain hinging means to be described and a set of line terminal sockets. It is to be understood that the broad features of this construction, as 20 claimed, are independent of the eccentrics as they may be dispensed with where it is possible to form accurate openings 34 in the box. In effect the eccentrics are portions of the tubes 32.

25 The line terminal sockets comprise the tubular members 32 which are adapted to receive the line wires. In order to hold the line wires in said sockets, the screws 41 are threaded through bosses formed with the 30 terminal members 29. Openings in the tubular members 32, aligned with the threaded openings for the screws 41, permit entry of said screws to hold the line wires.

As shown more particularly in Fig. 2, the 35 lower terminal member 29 is provided with a downward extension 43, the purpose of which is to support a hinge pin 45 on which hinges a clamp member 47, said member 47 passing around and clamping a tubular portion 49, the latter carrying integrally therewith a bottom 51. It is to be understood that other fastening means than said clamp 47 may be used. The tube 49 and bottom 51 form a cartridge support. The portions 49 and 51 are composed of insulating material. 45 They comprise a tubular cartridge support and a bottom.

Located within, and annularly spaced from the tube 49 is a cartridge tube 53 composed of insulating material, to which is held by means of a set screw 55, a terminal engaging element 57 for electrically engaging the lower spring clips 25. A slot 59 is machined in the side of the terminal engaging 50 element 57 for receiving one end of a fuse link 61, the other end of which link 61 is located at the upper end of the tube 53, the link having a hairpin turn 63 between its ends.

55 The set screw 55 also holds to the terminal engaging element 57 an outer guide ring 65 carrying a set screw 67 for holding in place the end of the short leg of the fuse link 61. A notch 66, cut in the upper periphery of 60 tube 49, is adapted to receive a corresponding

leg or extension 68, formed on the lower end of the guide ring 65, thereby determining the proper position of the guide ring, and consequently of the cartridge, on the tube 49, so that proper engagement may be effected between the terminal and the terminal engaging elements. From the above it will be seen that the tube 53, terminal engaging element 57, guide ring 65 and the fuse link 61 comprise a single unit. Added to this unit at the upper end is a cap or upper terminal engaging element 69 screwed to the tube 53 and provided with an anvil 71 against which anvil the upper end of the fuse link 61 lies so as to be engaged by a set screw 73 70 screwed oppositely through the cap 69 and tube 53. The cap 69 has fastened thereto an engaging loop 75 for purposes of applying a tool for opening the switch.

In operation, when the switch is to be opened the door 11 is first raised, the tool or hook applied to the ring 75 and the tool drawn downwardly, whereupon the tubular fuse unit is pulled through the dotted line position shown in Fig. 2. It will be noted 75 that tube 53 is drawn down as well as the outer annularly spaced tube 49 and the bottom 51. After the cartridge has been pulled down enough to clear the open door 11, the tube 53 is grasped and pulled outwardly, thereby withdrawing the terminal engaging element 57 and the guide ring 65 from the tube 49. A new cartridge may then be applied to the box or the old cartridge returned 80 with a new fuse.

In Fig. 4 is shown how the bottom of the annularly arranged tube 49 is provided with a series of lugs 77 for the purpose of spacing the tube 53 from the tube 49 even though it should have a tendency to misalign, due to 85 loose co-operation between the guide ring 65 and the tube 49. It will be noted from Fig. 2 that the relative elevation of the cartridge with respect to the tube 49 is controlled by the engagement indicated at numeral 79. It will 90 also be noted from Fig. 2 that the long and the short legs of the fuse link 61 are enclosed by tubular portions, the long leg by the tube 53 and the short leg by the tube 49, so that 95 when the fuse blows, all the gases will be ejected from the box instead of being trapped therein so as to tend to explode the switch.

When a fuse blows the reaction is upward, so that the porcelain or the like of the box is placed in compression only, due to the single upper suspension. The ring 65 closes the upper end of the outer annular tube 49 and the terminal engaging element 69 closes in the cartridge tube 53.

100 By means of the above construction it will be seen that extraneous and complicated fittings are eliminated and that a fewer number of parts have been caused to effect better results.

105 In view of the above, it will be seen that 130

the several objects of the invention are achieved and other advantageous results attained.

As many changes could be made in carrying out the above constructions without departing from the scope of the invention, it is intended that all matter contained in the above description or shown in the accompanying drawings shall be interpreted as 10 illustrative and not in a limiting sense.

We claim:

1. In a switch housing, a terminal support comprising a pin passing through openings in the sides of the housing, a fulcrum member within the housing rotatably mounted on the pin, said member supporting a terminal and extensions on said member on opposite sides of the pin, means in one of the extensions adapted to be forced into engagement with the housing, whereby the fulcrum member is fulcrumed on the opposite extension to force the pin against the sides of said openings to hold the pin in place.

2. In a switch housing, a terminal member comprising a tube passing through openings in the sides of the housing, a fulcrum member within the housing rotatably mounted on the tube, said member supporting a terminal, and extensions on said member on opposite sides of the tube, means in one of the extensions adapted to be forced into engagement with the housing, whereby the fulcrum member is fulcrumed on the opposite extension to force the tube against the sides of said openings to hold said tube in place and means for fastening line wires within the tube.

3. In a switch housing, a terminal member comprising a tube passing through openings in the sides of the housing, a fulcrum member within the housing movably mounted on the tube, said member supporting a terminal, at least one extension on the member and means thereon adapted to be forced against the housing to fulcrum the member on said extension, whereby the tube is moved to tightly engage the sides of said openings.

4. In a switch housing, a terminal support comprising a pin passing through openings in the sides of the housing, a fulcrum member within the housing and movably mounted on the pin, said member supporting a terminal, at least one extension on said member and means thereon adapted to be forced against the housing to fulcrum the member on said extension, whereby the pin is moved to engage the sides of the openings.

5. In a switch housing, a support comprising a pin passing through at least one opening in the housing, a fulcrum member movably mounted on the pin and at least one extension on the member with means on the fulcrum member adapted to be forced against the housing to fulcrum said member on the extension, whereby the pin is moved to tightly engage said opening.

6. In a switch device, a support comprising a pin passing through at least one opening in the device, a fulcrum member movably mounted on the pin and at least one extension on the member with means on the fulcrum member adapted to be forced against the device to fulcrum said member on the extension, whereby the pin is moved to tightly engage said opening, said fulcrum member supporting a terminal clip and hinging means for a cartridge support.

7. In a switch housing, a terminal support comprising a pin passing through openings in the sides of the housing, an eccentric mounted at each end of said pin within each opening, a fulcrum member within the housing and rotatably mounted on the pin, said member supporting a terminal and extensions on said member on opposite sides of the pin, means in one of the extensions adapted to be forced into engagement with the housing, whereby the fulcrum member is fulcrumed on the opposite extension to force the eccentric against the sides of said openings, whereby the pin is held in place.

In testimony whereof, we have signed our names to this specification this 14th day of August, 1928.
